UNITED STATES PATENT OFFICE

CARLOS E. HALL, OF RED MOUNTAIN, CALIFORNIA

ELECTRIC WELDING TONG

Application filed August 2, 1929. Serial No. 383,006.

My invention relates to improvements in single electrode welding tongs wherein one side of a direct current circuit is grounded to the work while the other side is connected thru a flexible power cable to the tong which holds the welding material.

Ordinarily, during the operation of welding, it is not feasible to turn the current off and on at the motor generator since the leads are long and the welding work is done at quite a distance from the generator. It is necessary and convenient, from time to time during the work, to lay aside the tongs, and if, in doing so, they come in contact with the grounded part of the work, such as the frame of a building, or the walls of a tank, a short circuit is developed which is undesirable, wasteful, and may damage or destroy the tongs.

One of the objects of my invention is to provide contacts within the body of the handle of the tong which will disconnect the tongs and all protruding metal parts from the power cable lead. Another object is to provide means whereby the contacts will remain in open position until positive actuation of the separation means by the operator. A further object is to provide contact elements, conveniently situated, within the handle body of the tong, capable of handling a large current of electricity without overheating or burning. Other objects will appear hereinafter.

I attain these objects by the device illustrated in the accompanying drawing in which:

Figure 1 is an assembled view of my improved tong, being in vertical elevation, and with the handle portion in section; Fig. 2 is a section of the tong supporting rod on line 2-2 Fig. 1; Fig. 3 is a section of the locking ring on line 3-3, Fig. 1. Fig. 4 is a perspective view of the locking ring.

Similar numerals refer to similar parts throughout the several views.

The welding bar gripping tong is composed of the stationary jaw 1, and the movable jaw 2, connected by hinge bearing 3 and held closed by spring 4. The lower portion of stationary jaw 1 forms a conductor bar 5, upon

which is formed the flange 6 having on its under side two oppositely positioned lugs 7. Below this flange the conductor bar is shaped into a cylindrical rod 8, which extends from between the lugs 7 through locking ring 9 into the hollow cylindrical handle 10. At its lower end the rod 8 is brazed into the conical contact element 11. The open spring 12 surrounds rod 8 within handle 10 and bears against ring 9 at its upper end and against the upper side of contact element 11 at its lower end. Within handle 10 and positioned below contact 11 is a cylindrical contact 14, on the lower end of which the rod 15 is formed. This rod extends through the insulating ring 16 and at its lower end is threaded to receive nut 17 and the power cable connecting sleeve 18. Ring 16 is held in place by screws 26 extending through handle 10.

The lower side of the contact element 11 is tapered to form a contact surface 19 in the shape of an inverted cone. Its sides are round and easily movable within handle 10 forming a guide for the lower end of rod 8. The upper side of contact element 14 is hollowed out so as to form a conical opening having a conical contact surface 20, adapted to receive and contact with surface 19 on element 11. By this means I secure a maximum contact surface together with a steady and aligning action of the lower end of rod 8. At the center of the conical opening in element 14, I provide a drilled depression 21 which prevents the tip of the element 11 from dubbing the center of the hollow and thus holding off full surface contact. This depression also provides a clearance so that in case the surfaces should become oxidized, or pitted by arcing, they may be resurfaced by inter-grinding.

The locking ring 9 is held in place by screws 22. It is provided with a circular hole 23 adapted to receive and act as a guide for rod 8. Oppositely positioned recesses 24 are formed on either side of this hole shaped to receive the lugs 7. Between these openings and on the upper face of ring 9 the notches 25 are formed adapted to engage lugs 7.

My tong is operated by inserting welding

bar between the jaws 1 and 2 by pressure on lever handle 27 in the conventional manner.

By turning the tong part of my device a quarter turn (in either direction) relative to the handle 10 the lugs 7 will be moved from notches 25 and will drop into recesses 24. The spring 12 will then force contact element 11 down and within contact element 14 thus holding and maintaining contact.

10 Figure 1, for the purpose of illustration, shows my tong in disconnected position. Lugs 7 rest in notches 25 and the contact elements 11 and 14 are separated. All metal parts of the tong are therefore dead and the 15 device may be laid anywhere about the work without fear of short circuit.

It is to be understood that the lower edges 20 of lugs 7 are smoothly rounded and that notches 25 are shaped to receive them having sufficient depth so that when the tongs are in disconnected position any ordinary jar will not dislodge the lugs from these notches. Handle 10 and ring 16 are made of insulating material such as fiber or bakelite while all 25 other parts are of suitable metal.

While my device may be generally considered a switch, I prefer to consider it an improved welding tong, wherein means for disconnecting the live exposed metal parts is 30 provided. A switch usually operates to open and close an electrical circuit, whereas my device is used rarely, if ever, to close or break the circuit. It is properly used to disconnect the welding bar tongs from the live lead after the bar has been taken from the work.

Since it is conceivable that various structural modifications might be made within the scope of my invention, I desire to be limited only by the following claims.

I claim:—

1. In a device of the kind disclosed, in combination, a welding bar tong supported on a conductor bar having a contact element at its lower end, an insulating handle containing a contact element adapted to engage said contact element on said conductor bar and having means of attachment to a power cable, a spring normally holding said contacts together, and disconnecting means comprising a plurality of lugs on said conductor bar and a locking ring having recesses adapted to admit said lugs whereby said contacts are enabled to be forced together by said spring, and notches intermediate said recesses on the upper face of said ring adapted to receive said lugs whereby said conductor and contact element supported thereon is held apart from said contact element in said handle, substantially as described.

2. In a device of the kind disclosed, in combination, an insulating supporting handle having at its upper end a guide ring, said guide ring having a centrally positioned round guide hole, and oppositely positioned openings on either side thereof adapted to

receive lugs, a tong adapted to hold a welding bar and having, at its lower end, a flange and a downwardly extending guide rod terminating in a conical electrical contact element, said flange having oppositely disposed lugs on its under side adapted to enter the openings on either side of the center hole of said guide ring, a fixed electrical contact element secured in the lower end of said handle having a conical recess in its upper end and adapted to make contact with the electrode on the lower end of said guide rod, together with means for attachment to an electrical power cable, and a spring surrounding said guide rod within said handle adapted to force said contacts together, substantially as described.

3. In an electric welding tong, in combination, a welding bar tong, supported on a conductor bar having a contact element at its lower end, and an insulating handle containing a contact element adapted to engage said contact element on said conductor bar, and having means of attachment to a power cable, a spring normally holding said contacts together, and disconnecting means comprising a plurality of lugs on said conductor bar, and a locking ring having recesses adapted to admit said lugs whereby said contacts are enabled to be forced together by said spring, substantially as described.

4. In a device of the character disclosed, in combination, a tong member having spring tensioned and manually adjustable jaws adapted to receive and hold a welding bar comprising its upper portion, a conductive bar terminating in a contact surface comprising its lower portion and oppositely positioned lugs intermediate said upper and lower portions, a handle member comprising an insulated sleeve, a ring plate at its upper end having an opening adapted to receive that portion of the conductive bar on said tong element extending between and below said lugs and having recesses adapted to receive said lugs, and a stationary conductive element comprising a contact surface at its upper end adapted to cooperate with said contact surface on said tong member, and resilient means whereby said contact surfaces are normally held in contact, substantially as described.

5. In a device of the kind disclosed, in combination, a tong element consisting of a conductive bar having spring actuated jaws adapted to hold a welding bar on its upper portion, and having a conductive contact element at its lower end and intermediately positioned lug projections, a handle element having an insulated sleeve, and a retaining ring at its upper end, said ring having an opening adapted to receive the conductive bar on said tong element, and recesses adapted to receive the lug projections on said conductive bar, and having a contact member contained

within said insulating sleeve, having a contact surface adapted to make electric contact with the conductive contact on said conductor bar, and on its outer portion, means for attachment to a conductor cable, and a spring operative intermediate said handle element and said conductive bar whereby said lug projections are forced into said recesses in said retaining ring and the said contact elements thereby pressed into contact.

6. In a device of the kind disclosed, in combination, a tong element consisting of a conductive bar having spring actuated jaws adapted to hold a welding bar on its upper portion, and having a conductive contact element at its lower end and intermediately positioned lug projections, a handle element having an insulated sleeve, and a retaining ring at its upper end, said ring having an opening adapted to receive the conductive bar on said tong element, and recesses adapted to receive the lug projections on said conductive bar, and having a contact member contained within said insulating sleeve, having a contact surface adapted to cooperate to make electric contact with the conductive contact on said conductor bar and on its outer portion, means for attachment to a conductor cable, and a spring operative intermediate said handle element and said conductive bar whereby said lug projections are forced into said recesses in said retaining ring and the said contact elements thereby pressed into contact, and means whereby said tong element may be raised against the pressure of said spring sufficient to separate said contact elements and fasten them in such raised position, substantially as described.

40 7. In a device of the character described, in combination, a tong element consisting of a conductor bar having spring actuated jaws adapted to hold welding metal at its upper end, a contact element at its lower end, and lugs intermediately positioned, a handle element comprising an insulated sleeve handle having positioned therein a stationary contact element having means on its outer portion for connection to an electric power cable, a ring positioned in the upper portion of said handle element having an opening adapted to receive the middle portion of said conductor bar, said opening having recesses adapted to receive the lugs on said conductor bar when in register, whereby said conductor bar is permitted longitudinal movement whereby contact with the contact element within said sleeve portion of said handle is made, said ring also having notches to receive said lugs when not in register with said recesses, whereby said contact elements are held apart, and spring means whereby said contacts are normally forced together, substantially as described.

65 8. In a device of the kind disclosed, in com-

bination, a handle element comprising an insulating sleeve containing a contact element having an inwardly positioned contact surface and means for attaching a power cable, a relatively movable conductive bar 70 with tongs at its upper end, and a contact element at its lower end, a locking mechanism intermediate said conductive bar and said handle comprising lugs on said conductive bar, and an opening in the end of said handle 75 element whereby said conductive bar may be forced against said contact within said handle element or locked out of contact therewith, and a spring-like element providing tension whereby said conductive bar is 80 normally forced toward the contact in said handle, substantially as described.

9. An electric welding tong comprising in combination, an insulating handle having an electric contact conductor affixed therein and 85 provided with threaded attachment means for connection to a power cable, a tong element movable within the upper end of said handle having bar gripping jaws at its outer end adapted to contact with the contact conductor in said handle, a spring operative intermediate said handle and said tong elements adapted to normally hold said contact elements resiliently together, and latching means including lugs positioned on said tong 90 element adapted to cooperate with recesses in said handle whereby when in register the contact portion on said tong element may be moved against the contact in said handle, but when rotatively displaced out of register said contacts are held apart against the pressure of said spring.
